DESIGN FOR A CONTAINER FOR THE DISPLAY OF EGGS

Louis Hendrich, Valparaiso, Ind.

Application February 15, 1934, Serial No. 50,745

Term of patent 7 years

To all whom it may concern:

Be it known that I, LOUIS HENDRICH, a citizen of the United States, residing at R. R. 6 Valparaiso, in the county of Porter and State of Indiana, have invented a new, original, and ornamental Design for a Container for the Display of Eggs, of which the following is a specification, reference being made to the accompanying drawing, forming part thereof.—

The figure is a perspective view of the container for the display of eggs, showing my design. The dominant feature of the design is the cover of the container, the container being conventional and illustrated in dotted lines.

I claim:

The ornamental design for a container for the display of eggs, as shown and described.

LOUIS HENDRICH.
